UNITED STATES PATENT OFFICE.

ANTIME MOTTEAU, OF BUENOS AIRES, ARGENTINA.

WINDOW.

1,343,520.

Specification of Letters Patent. Patented June 15, 1920.

Application filed July 18, 1918. Serial No. 245,517.

To all whom it may concern:

Be it known that I, ANTIME MOTTEAU, a citizen of the French Republic, residing at No. 1260 Garay street, Buenos Aires, Argentina, have invented certain new and useful Improvements in Windows, of which the following is a specification.

This invention relates to certain improvements in windows and its object is the provision of certain special means in combination with the window sashes and frames in order that the windows may be easily opened or closed.

The invention relates more specifically to the type of windows in which the sashes are vertically superposed, but it is obvious that my improvements may be also used in connection with windows in which the sashes are disposed of side by side, as will be clearly understood from the following description.

The main feature of my present invention consists in the fact that the entire window sash and its adjoining elements are rendered capable of an automatic raising or lowering by a combination of supporting devices—of which one is a pivot member and the other or others are sliding supports guided by suitable means provided on the window case or substantially in the same plane as the window case,—that is to say, each of the window sashes and its supporting means are always characterized by the fact that the sash has a pivotal movement about a fixed axis and one or more parts which slide along fixed guides, the said axis and guides being located on the window case or adjoining such window case in substantially the same plane as said case.

In order that it may be clearly understood and easily carried into practice, my invention has been illustrated in the accompanying drawings which show, in a more or less diagrammatic manner, some of the preferred embodiments of the same and in which similar characters of reference relate to the same or like parts throughout the several views.

In said drawings:

Figure 1 is a side elevation of one form of the invention, showing both sashes open, one side of the window frame being removed.

Fig. 2 is a similar view of a second form.

Figs. 3 and 4 are side elevations of a third form of the invention, with the sashes in open and closed positions, respectively.

Figs. 5 and 6 are corresponding views of still another form of the invention.

In the embodiment shown in Fig. 1, 1 is a window sash resting on pivots 2 at the ends of the supporting arms 3, said arms being pivoted at the opposite ends on a pivot rod 4 fixed in the window case 5. The upper end of sash 1 is provided with studs or journals 14 which are adapted to slide in guides 6; this sliding movement takes place in an upward or downward direction depending on the upward or downward displacement of the center of gravity of the window sash. A second rod or arm 7 is linked at 8 to each arm 3, the opposite end of said arm 7 having a stud or journal 14' to slide in a second guide 9.

The position of the pivotal point 2 with respect to the center of gravity of the window sash determines the automatic closing or opening of the sash and this displacement being reduced to a minimum, the respective movements take place smoothly and only a small effort is required in order to produce the opposite movement.

This opposite movement may be obtained, for instance, by means of a rope or chain 10, which is carried over a pulley 11 fixed to the window case and over a second pulley 12 fixed to the upper end of the window sash, the end of the rope or chain being finally fixed to a point 13 of the sash, conveniently outside the pivot point 2.

By pulling down the rope or chain 10 the sash is raised and the studs 14 slide upward in guides 6, the window sash rocking on pivots 2. The free end of the sash comes thus down until a perfect closure is effected. At the same time the arm or rod 7 turns upward on link 8 and its free end 14' slides in guide 9.

If the window is closed and the rope or chain 10 set free, there being always a small eccentricity between the points 2 and 4, the sash will tend to fall outward on account of gravity and the series of movements described will take place inversely. The sash will open up to the position shown in Fig. 1.

The window sash may be operatively connected with one or more similar sashes, as shown in said Fig. 1. To this end it is sufficient to connect corresponding points of two or more sashes of the same window.

In the embodiment shown, this connection takes place between two sashes by coupling two corresponding points 15 on the two sashes with each other by means of rods 16, and by connecting the two arms 7 by simi-

lar rods 17. As may be easily understood, the sashes may be actuated simultaneously by pressing or pulling upon the parts 10 or 17, or on any other point of the system, 5 for instance, on the sash 1.

It is obvious that according to my present invention, all the sashes of a window or only some of them, adjoining or not, may be operatively connected.

10 Fig. 2 shows another embodiment of my present invention. In this case, the window sash has a tendency to open on account of gravity. The closing is effected by pushing upward the sash. 4 is the pivot at the 15 upper end of arm 3, which arm is connected at 2 with the window sash 1.

Figs. 3 and 4 show another embodiment of the invention, with the window sashes open and closed respectively. The opening 20 of the window sash takes place due to gravity and the closing is effected by pulling on ropes 10 which are carried over the pulleys 20. When pulling on either rope 10, points 2 move in a direction toward 20, and the 25 studs 14 travel in the guides 6. The window sash rocks on 2 and passes to the vertical closed position, as shown in Fig. 4.

Figs. 5 and 6 show another embodiment of my present invention. The guide slots 6 30 are formed in inclined positions in the window case and the studs or journals 14, which are capable of sliding along the said guides, are each formed in one with an intermediate casting 17' fixed to the upper end of the 35 corresponding sash, so that the said upper end is capable of sliding almost in the plane of the said window case. The window case carries also a bearing 18 individual to each supporting rod 3 which is pivoted thereto. 40 The opposite end of the said rod 3 is pivoted to the said window sash at a point 2 which is so calculated as to lie a slight distance from the center of gravity of the window sash, in order to induce the downward, 45 movement of the said sash along the guides 6. The closing may be effected in any con-

venient manner, as for instance, according to the systems described with reference to the foregoing embodiments.

In the embodiments shown and described, 50 the window sashes may be operatively connected in any convenient order, as specified with reference to Fig. 1.

The invention is not limited to the specific forms as illustrated and described, and any 55 other form may be adopted within the scope of the following claim.

Independently of my present invention, the window sashes and cases may be constructed of any convenient material and 60 form.

What I claim is:

In a window, the combination of a frame having its side members provided with two pairs of upper and two pairs of lower 65 guides, the corresponding guides of said frame members confronting each other; upper and lower swinging sashes each provided at one end with a pair of pivots, the pivots of each sash being adapted to travel 70 along one of the corresponding pairs of guides; a pair of supporting rods for each sash pivoted at one end to the sash and at the other end to the frame at a point beyond the sash; a second pair of, supporting rods 75 for each sash pivoted at one end to the corresponding first-named rods and arranged at the other end to travel along the other pair of corresponding guides; a vertical member connected at opposite ends to the 80 sashes to cause both sashes to swing in unison and in the same direction when one sash is operated; and a vertical rod connected at opposite ends to the corresponding rods of the second-named pairs of support- 85 ing rods.

In testimony whereof I affix my signature in the presence of two witnesses.

ANTIME MOTTEAU.
